Primary Examiner — Clare E Heflin(57) **CLAIM**

The ornamental design for a light bar optical lens, as shown and described.

DESCRIPTION

FIG. 1 is a perspective view of a light bar optical lens showing our new design;

FIG. 2 is a front view thereof;

FIG. 3 is a back view thereof;

FIG. 4 is a right side view thereof;

FIG. 5 is a left side view thereof;

FIG. 6 is a top plan view thereof; and,

FIG. 7 is a bottom plan view thereof.

The broken line portions in FIGS. 1-7 are included to show unclaimed subject matter only and form no part of the claimed design.
